L. BINDER

BLANK FOR AND METHOD OF FORMING BOX BODIES

Filed Dec. 30, 1921

UNITED STATES PATENT OFFICE.

LOUIS BINDER, OF NEWARK, NEW JERSEY.

BLANK FOR AND METHOD OF FORMING BOX BODIES.

Application filed December 30, 1921. Serial No. 525,943.

To all whom it may concern:

Be it known that I, LOUIS BINDER, a citizen of the United States, and a resident of Newark, county of Essex, and State of New Jersey, have invented certain new and useful Improvements in Blanks for and Methods of Forming Box Bodies, of which the following is a specification.

This invention relates to an improved box, and is particularly adapted for the manufacture of cigar boxes of heavy cardboard which is not easily broken on a line of scoring, the invention being particularly directed toward the blank from which the box is made.

The object of the invention is to provide a box which will withstand the pressure incidental to packing cigars in the box, and one in which the bottom and the ends are substantially stiff.

A clear understanding of the invention can be secured by reference to the accompanying drawing, in which Figure 1 is a perspective view of a blank cut preparatory to folding, and with a sheet used at one of the end walls shown slightly separated therefrom. Figure 2 is the blank shown in Figure 1, but on a slightly reduced scale and turned over ready for folding, with the strengthening sheets on the front wall and the end walls of the box in position. Figure 3 is a detail perspective view of the juncture of the bottom and one of the wings of the blank. Figure 4 is a similar view with the parts bent or folded at right angles. Figure 5 is a view similar to Figure 4, with the bottom pushed in and the bottom sheet in position. Figure 6 is a perspective view of the bottom sheet, and Figure 7 is a perspective view of a completed corner of the box.

The box, which is adapted to be made from the blank described and shown herein, is of heavy material, and in the drawing I show a blank comprising a bottom 10, wings 11 and 12 to form the front and back, respectively, of the box, and 13 and 14 to form the end walls of the box when they are folded upward from the bottom 10.

In preparing the blank, and usually while cutting it out, it is also provided with cuts 15 which are arranged at where the juncture of the bottom and of the wings, which will form the walls, is placed. Such cut is shown more in detail in Figure 3, and it will be noticed that it extends more than half way through the material; in fact it usually ex-

tends about three-quarters of the way through the material so as to define the place of folding, making the folding comparatively easy, and providing the abutting portions, after they are folded, with sharp corners, which, it will be understood, materially enhances the appearance of the box.

The cuts 15 are preferably made all at one time by means of a set of blades, and the cuts at *a*, which are the cuts that are placed at the juncture of the end walls 13 and 14 and the bottom 10, are inset from the ends of the wings 11 and 12 so that when the wings are folded up the walls 11 and 12 will engage the side edges of the wings 13 and 14.

In cutting these boxes it is usual to dispose the material that is being cut so that the grain of the fibre, which is shown by surface shading in Figure 1, is longitudinal of the bottom and of the walls 11 and 12, but this disposition makes it transverse to the wings 13 and 14. The material is substantially stiff when it is bent across the grain, but is brittle and easily breaks when broken with the grain.

To overcome the weakness in the walls 13 and 14, sheets 16, which can be of thinner material but are usually of cardboard, are fastened, usually by pasting them, on what will be the outer faces of the end walls 13 and 14, and they are usually made long enough so that they project beyond and will engage the ends of the wings 11 and 12 when they are folded up to form the front and back walls of the box. The sheet, after being so strengthened, is turned over, as shown in Figure 2, and is then folded up so that the wings are vertical, the folding, of course, taking place at the weakened portion in line with the cuts 15, the folded portion being shown in Figure 4, so that sharp corners 17 and 18 are provided, and after the end walls are folded so as to be perpendicular to the bottom 10, the bottom is pushed in, as shown in Figure 5, from the position shown in Figure 4, the weakened portion forming a small web that engages the parts even after the bottom 10 is pushed

inward, and since the bottom 10 has a normal tendency to again move outward from between the folded wings, I place a strengthening sheet 19 which is of substantially the same size as the bottom of the box and which is securely pasted to the bottom, as shown in Figures 5 and 7.

The usual corner bindings used on boxes of this kind have been omitted from the drawing as they are no part of the invention, but it will be understood that they are used as 5 the trade now uses them in holding the parts in their relative positions.

When cigars are placed in boxes they are pressed after they are placed in the box, and the pressure is particularly strong against 10 the end walls 13 and 14, since the bulging of the contents is in that direction as the cigars are laid transversely in the box. This outward pressure does not distort the present box because the sheets 16, with the fibre of 15 each sheet at an angle to the fibre of the wall to which it is attached, prevents the buckling or splitting usual in heavy cardboard boxes used as cigar boxes which have been heretofore employed.

20 The cutting and the folding, as shown in Figures 3, 4, 5 and 7, provides sharp corners on all the corners of the box, which not only provides a better appearance, but makes it possible to more securely paste the parts together, and, as will be seen from Figure 7, 25 the abutment of the sheet 16, where it projects beyond the end wall, is fitted snugly against the ends of the front and rear walls so that any inward movement of the walls is 30 thus resisted.

In cases of heavier boxes I may place a strengthening sheet 20 on what will be the outer face of, say, the front wall.

I claim:

35 1. A box body formed of a blank of heavy cardboard having a central body portion, and wings to form end and side walls, the abutting parts of said portions being defined by cuts extending nearly through the material, and sheets of material secured to the

outer faces of the end walls and adapted to abut on the ends of the side walls, the grain of the fibre in a sheet being at an angle to the grain of the wall.

2. A box body formed of a blank of heavy 45 cardboard having a central body portion, and wings to form end and side walls, the abutting parts of said portions being defined by cuts extending nearly through the material, and a sheet of material fastened to 50 each end wall and arranged so that the grain of its fibre is at an angle to the grain of the wall.

3. The method of forming a box which consists in the provision of a blank to form 55 the bottom and the sides of the box, cutting through said blank from its bottom face through the major portion of the material where the juncture of the bottom and the side walls is, folding up the side walls from 60 the bottom, pushing in the bottom so that its bottom face is even with the bottom edges of the box, and then affixing a sheet to cover the bottom and said bottom edges to retain 65 said bottom in its inserted position.

4. The method of forming boxes of heavy 70 cardboard consisting in the provision of a blank to form the bottom and the sides of the box, cutting into said material more than half way through it, affixing sheets to the end walls of the box on the outside thereof and projecting therefrom so that when folded the sheets will engage the ends of the side walls, and then folding the walls up 75 from the bottom at the cut portions.

In testimony that I claim the foregoing, I have hereto set my hand, this 28th day of December, 1921.

LOUIS BINDER.
